Primary Examiner — Justin C Dodson*Assistant Examiner* — Sydney M Evans(74) *Attorney, Agent, or Firm* — Nelson Mullins Riley & Scarborough LLP(57) **CLAIM**

The ornamental design for a load binder substantially as shown and described.

DESCRIPTION

FIG. 1 is a front perspective view of a new, original, and ornamental design of a load binder in accordance with the present design;

FIG. 2 is a left side elevation view thereof;

FIG. 3 is a right side elevation view thereof;

FIG. 4 is a back elevation view thereof;

FIG. 5 is a front elevation view thereof;

FIG. 6 is a top plan view thereof; and,

FIG. 7 is a bottom plan view thereof.

The portion of the article between the break lines forms no part of the claimed design.
